OUTBOARD MOTOR WELL AND GUARD

Morton D. Cohen, Minneapolis, Minn.

Application August 11, 1952, Serial No. 303,733

13 Claims. (Cl. 115—41)

1

This invention relates to boats. More particularly, it relates to an outboard motor well and guard for use on a boat.

One of the most frequent inconveniences experienced by fishermen and others who use outboard motors on boats is the requirement for replacement of a shear pin in the propeller shaft of the motor after an obstruction such as a log or rock has been encountered by the propeller. The replacement of a shear pin in a propeller shaft while out on the water in a boat is both difficult and time consuming and a source of annoyance to the user of the motor. My invention is directed toward the elimination of such a requirement for all time.

It is a general object of my invention to provide a combined outboard motor well and guard which will eliminate the need for replacing a shear pin every time an obstruction is passed over with the boat upon which the motor is mounted.

A more specific object is to provide a combined outboard motor well and guard which will positively guard the propeller of the motor and preclude the possibility of its shear pin being sheared.

A still more specific object is to provide a combined outboard motor well and guard which, when an obstruction is passed over with the boat, will automatically cause the outboard motor to be lifted to a clearing position above the obstruction.

Another object is to provide a combined outboard motor well and guard which, when an obstruction is passed over with the boat, will cause the outboard motor to be raised to an elevated position so as to clear the obstruction and will simultaneously maintain a guard between the obstruction and the propeller of the motor.

Another object is to provide an outboard motor well and guard which will normally hold the outboard motor in fixed position relative to the boat but will release the motor for vertical movement relative to the boat when the boat rides over an obstruction and which will thereafter re-engage the motor and again hold it in fixed position relative to the boat.

These and other objects and advantages of my invention will more fully appear from the following description, made in connection with the accompanying drawings, wherein like reference characters refer to the same or similar parts throughout the several views, and in which:

Fig. 1 is a vertical sectional view of one embodiment of my invention with the motor shown in side elevation taken along approximately line 1—1 of Fig. 2;

2

Fig. 2 is a horizontal sectional view taken approximately along line 2—2 of Fig. 1;

Fig. 3 is a fragmentary detailed view on an enlarged scale of the latch mechanism shown in the embodiment of Figs. 1 and 2;

Fig. 4 is a fragmentary detailed view on an enlarged scale showing the guideway and one slidable motor support which may be used in conjunction therewith;

10 Fig. 5 is a fragmentary detailed view on an enlarged scale showing the guideway of the embodiment shown in Figs. 1 and 2 and a different type motor support for use in conjunction therewith;

15 Fig. 6 is a fragmentary detailed view on an enlarged scale showing a third type of slidable motor support which may be used in conjunction with the guideway of the embodiment shown;

20 Fig. 7 is a fragmentary detailed view on an enlarged scale showing the fourth type of slidable motor support which may be used in conjunction with the guideway of the embodiment shown;

Fig. 8 is a vertical sectional view of a second 25 embodiment of my invention with the motor shown in side elevation and taken along approximately line 8—8 of Fig. 9;

Fig. 9 is a horizontal sectional view of the second embodiment taken approximately along line 30 9—9 of Fig. 8;

Fig. 10 is a fragmentary side elevational view of the lower end portion of an outboard motor with a guard mounted thereon in accordance with my invention for use with the motor well and slidable motor support as shown in Figs. 8 and 9.

One embodiment of my invention as shown in Figs. 1—3, may include a boat (not shown in full) having a bottom 11 with an opening 12 formed therein. Secured to the bottom 11 of the boat in upstanding position by bolts 13 which pierce the same, is a tubular member 14 having the same shape as the opening 12 and of a diameter equal to that of the opening. This tubular member 14 has an outwardly extending flange 15 at its lower end which abuts against the underside of the bottom 11 of the boat when the member is mounted thereupon as best shown in Fig. 1. When so positioned the tubular member 14 extends upwardly through the bottom of the boat and the flange 15 cooperates with a ring member 16 which surrounds the tubular member to hold the tubular member in upstanding position. Gaskets 17 and 18 are positioned between the ring member 16 and the bottom 11 and the flange 15 and the bottom 11 so as to prevent

leakage of water into the boat. The tubular member 14 is of sufficient length so as to extend upwardly a substantial distance above the bottom of the boat and above the level of the water outside the boat. It is obvious, of course, that the tubular member 14 will be of sufficient length if it extends up to the level of the upper edge of the boat or thereabout. The embodiment shown in Figs. 1-3 utilizes a tubular member which is rectangular in shape and has opposed side walls 14a, a forward wall 14b and a rear wall 14c.

Extending inwardly from the opposed side walls 14a adjacent the rear wall 14c of the tubular member 14 are two opposite inwardly extending flanges 19 and 20 which together provide a guideway hereinafter designated as G. Mounted in this guideway G in free sliding relation thereto is a motor support panel 21, the upper central portion 22 of which is cut free from the more lateral portions and bent inwardly as best seen in Fig. 1, and is then bent upwardly to provide a vertical portion 23 adapted to receive the motor M thereupon. The upper side of the lateral portions 24 and 25 of the motor support panel 21 may be a plain panel as best shown in Fig. 4 which slides within the guideway G and causes the motor support panel 21 to be maintained in vertical position for free sliding vertical movement when required. These side or similar portions 24 and 25 may be provided with rollers 26 which extend laterally thereof, as shown in Fig. 5 to facilitate the vertical sliding movement of the motor support panel relative to the tubular member 14. If desired, a plurality of rollers may be provided for each of these side portions so that there is one laterally disposed roller 27, one forwardly disposed roller 28 and one rearwardly disposed roller 29. The forwardly disposed roller 28 is positioned to move within a groove 30 formed in its respective flange and the rearwardly disposed roller is positioned to move vertically in an opposite groove 31 in the rear wall 14c. This may best be seen in Fig. 6. Another modification of the manner of mounting the motor support panel 21 is seen in Fig. 7 wherein plastic blocks 32, 33 and 34 are provided at the side of the motor support panel to move in grooves provided therefor to facilitate the vertical movement of the support panel. The motor M is solidly affixed to its clamp 67 and is not allowed to move relative to clamp 67 about pin 68.

Connected to the motor support panel 21 is a mechanism indicated generally as 35 for moving the support panel 21 and the motor M vertically when an obstruction is encountered by a part of the mechanism 35 which extends downwardly beneath the bottom 11 of the boat. This mechanism 35 includes a pair of opposed laterally spaced feeler members 36 each of which is pivotally mounted at its upper end portion upon the lower end of the tubular member 14 as at 37. Each of the feeler members 36 has a rearwardly extending normally horizontal arm 38 the free end 39 of which is pivotally connected by a pivot pin 40 to a link 41 which in turn is pivotally connected at its upper end to the upper side portions 24 or 25 as at 42. A spring 43 connects each of the pivotal connections at 40 to the upper end portion of the tubular member on the opposite side. This spring 43 constantly urges the portion of the arm 38 and the link 41 adjacent the pivotal connection upwardly in the direction in which the spring extends. A pair of stops 44

and 45 extend inwardly from the side walls 14a of the tubular member 14 to prevent the arms 38 and the links 41 from moving to or beyond dead-center position.

5 Mounted on the two opposed feeler members 36 and extending therebetween is a plurality of rearwardly declining deflector plates 46 to which rigidity is provided by means of a plurality of vertical rods 47 arranged as best shown in Figs. 1 and 2. By referring to Figure 2 it can be seen that the deflector plates together form a V-shaped open framework structure which serves as a deflector and a guard to prevent obstructions from encountering the propeller 48 of the motor M.

10 Holding the motor support panel 21 normally fixedly relative to the tubular member 14 is a latch mechanism indicated generally as L and which includes a housing 49 which is mounted upon the flange 15 of the tubular member 14 in depending position. Within the housing 49 is a U-shaped latch element 50 adapted to engage the motor support panel 21 in a notch 51 provided therein for that purpose. This latch element 50 is constantly urged forwardly to latching position by a spring 52 and is pivotally connected by a link 53 to the upper and swinging portion of one of the panel members 36.

15 Figs. 8 and 9 show a second embodiment of my invention wherein the boat bottom 55 has a circular opening 56 therein adapted to receive a tubular member 57 which is circular in cross-sectional shape and has an outer diameter substantially equal to the diameter of the opening. 20 This tubular member 57 has a second tubular member 58 mounted therein in free sliding relation, the external diameter of this second tubular member being slightly smaller than the internal diameter of the tubular member 57. A pair of 25 outwardly extending stops 59 prevent the second tubular member 58 from passing downwardly through the tubular member 57. A motor support in the form of a cross-sectional panel 60 extends across the interior of the second tubular member 58 and is adapted to have the motor M mounted thereupon.

30 Secured to the lower end portion of the second tubular member 58 is an open framework wire cage 61. As can best be seen in Fig. 8 this wire cage completely encircles the propeller 48 of the motor M and is curved so as to provide a deflecting surface as at 62 to cause the second tubular member 58, its motor support 60 and the motor M to ride upwardly in a free manner when an obstruction is engaged by the lower end portion of the wire cage 61.

35 In order to facilitate the action of such an outboard motor well and guard in a boat, I have invented a different type of steering device for use on the motor M. As can best be seen in Figs. 1 and 8, this device consists of a steering wheel 63 which completely encircles the propeller shaft carrying the propeller 48 and permits the motor to be guided readily and easily from any position relative thereto. This precludes the interference of the steering operation by other persons sitting adjacent to the motor well while the boat is moving through the water. The type of steering device provided on most conventional outboard motors is one where-40 in a handle extends outwardly from the motor. Such a steering device is entirely unsatisfactory where the motor is positioned in the central portions of the boat as is contemplated in the use 45 of my invention.

Shown in Fig. 10 is an open framework wire cage 64 which is fixedly mounted upon the housing 65 of the propeller shaft carrying the propeller and completely encircling or surrounding the propeller. This cage 64 also has a curved surface 66 which is adapted to protect the propeller and cause the motor to ride upwardly over an obstruction when the motor is mounted on the motor support 60.

In operation, the motor M is mounted upon the motor support panel 21 in the manner shown in Fig. 1. The latch mechanism L normally holds the motor support panel 21 against relative vertical movement with respect to the tubular member 14. As the boat moves forwardly through the water the deflector plates 46 direct the water downwardly toward the propeller and away from the open lower end of the tubular member 14. The feeler members 36 along with the rods 47 act as a feeler to engage any obstructions or obstacles over which the boat may pass. If such an obstruction or obstacle is encountered the feeler members 36 are urged rearwardly by the obstacle and they commence to pivot upon their pivot at 37 whereupon the link 53 of the latch mechanism L urges the latch element 50 rearwardly to the dotted line position shown in Fig. 3. This movement is against the movement of the spring 52 and withdraws the latch element from the notch 51 formed in the motor support panel 21 so that the support panel is free to move upwardly. Simultaneously, the arm 38 is swung upwardly, this upward movement causing the link 41 to urge the motor support panel 21 vertically relative to the tubular member 14. This moves the motor support panel 21 upwardly and carries the motor M therewith to an elevated position so that the obstacle or obstruction will be cleared by the propeller 48 of the motor M. In this manner the obstruction or obstacle is avoided and there is no possibility that the shear pin which drivably connects the propeller shaft and the propeller 48 being sheared. The spring 43 aids in causing the motor support panel 21 to be moved upwardly by tending to cause the arm 38 to swing upwardly and to move the link 41 upwardly therewith.

As the feeler members 36 swing rearwardly they at all times remain in guarding position relative to the propeller 48 so that there is no possibility of the obstacle or obstruction coming in contact with the propeller. In addition, the feeler members 36 together with the rods 47 and the deflector plates 46 normally prevent heavy weeds from engaging the propeller 48 and causing it to markedly lose power.

After the obstruction or obstacle has been passed over, the weight of the motor is sufficient to cause the motor support panel 21 to again descend to the position shown in Fig. 1. When it has reached this position the latch element 50 again re-engages the motor support panel 21 and holds the same in fixed position relative to the tubular member 14.

When the embodiments shown in Figs. 8-10 are utilized, the second and inner tubular member 58 is free to move upwardly relative to the tubular member 57 at all times but is prevented from moving downwardly beyond a predetermined position by the stops 59. When an obstacle is encountered by the open framework guard 61 the curved surface thereof tends to cause the tubular member 58 to move upwardly relative to the outer tubular member 57. After the obstruction has been passed over, the weight

of the motor M is sufficient to cause the tubular member 58 and the motor support 60 to again descend to the position shown in Fig. 8. The cage 61 prevents the propeller 48 from engaging such an obstruction or obstacle and causing the shear pin to be sheared. At the same time, it positively acts as a guard against heavy weeds becoming entangled in the propeller.

Thus it can be seen that I have provided a novel device for mounting an outboard motor upon a boat to positively prevent damage to the motor when an obstruction or obstacle is passed over by the boat. It can be readily seen that the slideable motor support panels provided in my device and the panel mechanism cooperate to positively prevent any serious injury to the propeller of the motor as a result of encountering an obstruction. It should be noted that my device moves the propeller to a position completely out of danger and automatically provides for it returning to its original position. Thus it can be readily seen that I have provided an outboard motor well and guard which effectively eliminates the need for replacing a shear pin every time an obstruction is passed over by the boat and is engaged by the propeller of the motor mounted thereupon. It should also be noted that my device at all times maintains a guard relative to the propeller 48 while the motor and its propeller are being elevated to an out-of-way position. At the same time, I have provided a mounting for a motor which enables the motor to be used to drive the boat in either direction and which will facilitate the use of such a motor in any portion of the boat whatsoever.

In addition to the advantages outlined above, it should be noted that my outboard motor well and guard substantially eliminates the danger of the operator of the motor from falling overboard, since the outboard motor is now positioned in the middle of the boat and there is no longer any requirement for the operator to lean outwardly over the water to perform repairs on the motor or to disentangle the propeller after a line has become entangled therewith. In addition, the danger of the boat tipping as a result of the use of a high-powered motor has been substantially eliminated, since the motor is now positioned adjacent the central portion of the boat instead of at one end thereof. Also, the danger of the motor becoming disengaged and lost has been eliminated. Each year many motors become disengaged from the rear end of boats and are lost in the water as a result.

Other advantages of my device for mounting an outboard motor upon a boat include the substantial reduction of the danger of fire, for the motor is at no time tilted so that gasoline will run out of its tank when used in conjunction with my device. It is possible for an individual of relatively moderate means to have all the advantages of an inboard motor without the expense which is normally attendant therewith. In addition, my device eliminates undue and sudden stresses upon the rear of the boat which over a period of time tend to weaken the boat. At the same time the boat is considerably more stable when the motor is used in conjunction with my device adjacent the central portion of the boat.

It will, of course, be understood that various changes may be made in the form, details, arrangement and proportions of the various parts without departing from the scope of my invention.

What is claimed is:

1. A combined outboard motor well and guard comprising a tubular member adapted to be mounted in upwardly extending position upon the bottom of a boat with the interior thereof communicating through the bottom of the boat with the water therebelow, a motor support slidably mounted within said tubular member for vertical movement relative thereto, and mechanism connected to said support and depending relative thereto for moving said support and the motor supported thereby upwardly when an obstruction is encountered by said mechanism.

2. A combined outboard motor well and guard comprising a tubular member adapted to be mounted in upwardly extending position upon the bottom of a boat with the interior thereof communicating through the bottom of the boat with the water therebelow, a motor support slidably mounted upon said tubular member for vertical movement relative thereto and in position to support a motor within said tubular member, a swingable feeler member depending from said tubular member, and linkage mechanism connecting said feeler member and said support and functioning to move said support and the motor supported thereby upwardly when an obstruction is encountered by said feeler member.

3. The combination of a boat having a bottom with an opening therein, a tubular member mounted upon the bottom of said boat and extending upwardly therefrom with the interior thereof communicating via the opening in said boat with the water therebelow, a motor support slidably mounted within said tubular member for vertical movement relative thereto, and mechanism connected to said support and depending therefrom for moving said support and the motor supported thereby upwardly when an obstruction is encountered by said mechanism.

4. The combination of a boat having a bottom with an opening formed therethrough, a tubular member mounted in upwardly extending position upon the bottom of said boat with the interior thereof communicating with said opening, a motor support slidably mounted within said tubular member for vertical movement relative thereto, a swingable feeler member connected to said tubular member and extending downwardly therefrom, and linkage mechanism connecting said feeler member in driving relation to said support for moving said support and the motor supported thereby upwardly when an obstruction is encountered by said feeler member and the latter is swung by the obstruction.

5. A combined outboard motor well and guard comprising a tubular member adapted to be mounted in upwardly extending position upon the bottom of a boat with the interior thereof communicating through the bottom of the boat with the water therebelow, a guideway carried by said tubular member, a motor support slidably mounted within said guideway for vertical movement relative thereto and in position to support a motor within said tubular member, and mechanism connected to said support and extending downwardly relative to said tubular member for moving said support and the motor supported thereby upwardly when an obstruction is encountered by said mechanism.

6. A combined outboard motor well and guard comprising a tubular member adapted to be mounted in upwardly extending position upon the bottom of a boat with the interior thereof communicating through the bottom of the boat

with the water therebelow, a guideway carried by said tubular member, a motor support slidably carried by said guideway within said tubular member for vertical movement relative thereto, 5 a feeler member swingably mounted adjacent the lower end portions of said tubular member and extending downwardly therefrom, and linkage mechanism connecting said feeler member to said support in operating relation and functioning to move said support and the motor supported thereby upwardly when an obstruction swings said feeler member.

7. A combined outboard motor well and guard comprising a tubular member adapted to be mounted in upwardly extending position upon the bottom of a boat with the interior thereof communicating through the bottom of the boat with the water therebelow, a motor support slidably mounted within said tubular member for vertical movement relative thereto in position to permit such a motor to extend through the bottom of the boat and into the water therebelow, a swingable feeler member connected with said support and depending from said tubular member adjacent the lower end portion thereof, and linkage mechanism connecting said swingable feeler member in driving relation to said support to cause said support and the motor supported thereby to move upwardly when an obstruction swings said feeler member.

8. A combined outboard motor well and guard comprising a tubular member adapted to be mounted in upwardly extending position upon the bottom of a boat with the interior thereof communicating through the bottom of the boat with the water therebelow, a guideway mounted within said tubular member, a motor support slidably mounted within said guideway for vertical movement relative thereto, a feeler member 35 pivotally connected to the lower end portion of said tubular member and depending therefrom, said feeler member having an upper end portion, and linkage mechanism extending between the upper end portion of said feeler member and said support and moving said support and the motor supported thereby upwardly when an obstruction causes said feeler member to pivot.

9. A combined outboard motor well and guard comprising a tubular member adapted to be mounted in upwardly extending position upon the bottom of a boat with the interior thereof communicating through the bottom of the boat with the water therebelow, a guideway carried by said tubular member, a motor support slidably mounted within said guideway for vertical movement relative thereto, a feeler member pivotally mounted upon the lower end portion of said tubular member and depending therefrom, linkage mechanism connecting said feeler member in driving relation to said support and causing said support and the motor supported thereby to move upwardly when said feeler member is caused to pivot by an obstruction encountered, and latch mechanism connected to said motor support and normally holding said motor support in fixed position relative to said tubular member and functioning to release said support when said feeler member pivots.

10. A combined outboard motor well and guard comprising a tubular member adapted to be mounted in upwardly extending position upon the bottom of a boat with the interior thereof communicating through the bottom of the boat with the water therebelow, a guideway carried by said tubular member, a motor support slidably

mounted within said guideway for vertical movement relative thereto and relative to said tubular member, a feeler member pivotally mounted adjacent the lower end portion of said tubular member and depending therefrom, linkage connecting said feeler member in driving relation to said support and causing said support and the motor supported thereby to be moved upwardly when said feeler member pivots, a latch member normally holding said support fixed relative to said tubular member, and a link connecting said latch member to said feeler member and functioning to release said latch member when said feeler member pivots.

11. A combined outboard motor well and guard comprising a tubular member adapted to be mounted in upwardly extending position upon the bottom of a boat with the interior thereof communicating through the bottom of the boat with the water therebelow, a motor support slidably mounted within said tubular member for vertical movement relative thereto, a feeler member pivotally mounted upon the lower end portion of said tubular member and depending therefrom ahead of the motor, and linkage mechanism connecting said feeler member in driving relation to said support and causing said support and the motor supported thereby to move upwardly when said feeler member is pivoted by an obstruction encountered thereby, said feeler member including a plurality of rearwardly declining deflector elements adapted to direct the water downwardly and away from the opening in such a boat.

12. A combined outboard motor well and guard comprising a tubular member adapted to be mounted in upwardly extending position upon the bottom of a boat with the interior thereof communicating through the bottom of the boat

with the water therebelow, a motor support slidably mounted within said tubular member for vertical movement relative thereto, and a curved open framework guard connected to the lower portions of said motor support and depending therefrom and extending around the propeller of the motor to guard the same and to cause said motor support to move upwardly when an obstruction is encountered thereby.

13. The combination of a combined outboard motor well and guard comprising a tubular member adapted to be mounted in upwardly extending position upon the bottom of a boat with the interior thereof communicating through the bottom of the boat with the water therebelow, a motor support slidably mounted within said tubular member for vertical movement relative thereto, a motor mounted on said support and extending downwardly through said tubular member with its propeller a substantial distance below the bottom of the boat, and a curved open framework guard connected to said motor and extending around the propeller of said motor to guard the same and to move said support and said motor upwardly when an obstruction is encountered by said guard.
